OIL FUSE CUT-OUT

Andrew E. Papp, Chicago, Ill., assignor to G & W
Electric Specialty Co., Chicago, Ill., a corpora-
tion of Illinois

Application May 15, 1935, Serial No. 21,554

37 Claims. (Cl. 200—120)

My invention relates to electric fuse devices and particularly to a type of fuse using oil in connection with the fuse and commonly known as an oil fuse or cutout.

5 One of the objects of the invention is to provide a simple, practical and advantageous type of electric fuse and particularly an oil fuse or cutout.

Another object of the invention is to secure 10 simplicity of construction with consequent low cost of manufacture and maintenance.

Another object of the invention is to secure a high degree of efficiency of operation.

Another object of the invention is to permit 15 the ready assemblage and disassemblage of the device.

Another object of the invention is to arrange for the quick and easy replacement of a fuse when one has blown.

20 Another object of the invention is to prevent accidents by short circuits in manipulating the device.

Other objects of the invention will appear and be pointed out hereinafter.

25 In the accompanying drawings:

Figure 1 is a longitudinal section of an oil fuse or cutout embodying my invention, said section being taken on the line 1—1 in Figure 2;

Figures 2, 3 and 4 are cross-sections taken on 30 the lines 2—2, 3—3 and 4—4 respectively in Figure 1;

Figures 5 and 6 are cross-sections taken on the lines 5—5 and 6—6 in Figure 4; and

Figure 7 is a detailed view of construction.

35 In the accompanying drawings I show a cutout involving a casing 1 which is preferably made of metal and forms the main body of the device. This casing 1 is preferably to receive oil or other liquid insulating material for purposes 40 in connection with fuses of this kind.

The lower portion of this casing 1 is preferably provided with apertures in which are fitted insulators 2—2 for the reception of conductors forming part of the circuit which is to include 45 the fuse.

As a preferred arrangement, these insulators 2 are provided with shoulders 3 and separated from the casing 1 by packing washers 4 which make oil and air tight joints between the insulators and said casing 1. Other packing washers 5 are imposed between rings 6 which are secured by bolts 7 to the casing 1 so as to hold the insulators 2 firmly and tightly in proper position.

55 Each insulator 2 is preferably provided with a

terminal 8 having a socket 9 for a conductor, and this terminal 8 is provided with an extension 10 which may be extended up through an aperture in the upper end of the insulator and secured to a post 11, the extension 10 and post 11 being preferably screw-threaded so that the post 11 may be firmly screwed into position on top of the insulator 2 and in firm electrical contact with the extension 10 and terminal 8. A washer 12 of packing or like material is preferably imposed between the enlarged lower end 13 of post 11 and top of insulator 2 so as to make a tight joint at the upper end of the insulator. The insulated conductor (not shown) may be led into the lower end of the insulator 2 and secured to the terminal 8 so as to make good electrical connection with terminal 8 and post 11 and thus by the two insulators 2—2 and their terminals and cooperating parts, provision is made for the connection of two conductors which are to include the fuse of this device in their circuit.

The upper end of casing 1 is preferably made open, having one flange 14 with an opening 15 and another flange 16 with an opening 17, and into this open end of the casing 1 a fuse carrying cartridge 18 may be fitted, arrangement being made whereby this cartridge may be inserted into the open end of the casing 1 to place the fuse in position in the latter, and also whereby the cartridge may be withdrawn either to withdraw the fuse or to provide the cartridge and therefore the circuit with a new one after the fuse has been blown.

This cartridge is preferably composed of a handle portion 19 provided with opening 19a and a body portion 20 which is adapted to fit in the opening 17 formed by the flange 16. The body portion 20 has the laterally extending and oppositely disposed flanges 20a adapted to be received in the openings 20b formed in the flange 14 of the casing 1. Upon rotation of the cartridge 18 (as will be later more fully described), flanges 20a are moved beneath flange 14. This body portion 20 has an extension 21 adapted to extend inwardly, and this extension carries a hollow or chamber member 22 having a chamber 23 and side openings 24 whereby the interior of chamber 23 may be in communication with the interior of casing 1 and therefore may contain oil when the latter is provided with oil.

A fuse 25 is shown carried by the member 22 and extended across the chamber 23 and having its ends passing through apertures 24, so that the fuse is not only carried by the cartridge member 20 but is also immersed in oil when the de-

vice is in operative condition. The member 22 is preferably of some insulating material, as for example Ebonite, so as to afford good insulation for the fuse 25 and its associated parts.

- 5 The fuse 25 is preferably subjected to spring pressure tending to elongate so that when it blows the spring pressure or action will tend to separate the fuse or its parts and thereby lengthen the fuse gap and elongate the arc. As 10 a simple and advantageous arrangement, spring members 27 (Figure 7) are preferably mounted on the chamber member 22 and interposed between the fuse and said member 22 so that they tend to spring outwardly and thereby exert a 15 pressure on the fuse tending to elongate it. These springs 27 may be held in position by screws 29, passing through apertures 30 in the spring and these screws also hold the ends of the fuse in place, passing through apertures 20 31 of the same. This mounting is shown best in Figures 1, 3, 4, 5 and 6, particularly in Figure 3. The screws 29 are preferably provided with wing nuts 32 and are mounted on side portions or extensions 33 and 33a of the chamber member 22. 25 Each screw 29 is provided with a hex or like nut 34 and an enlarged threaded inner end 35 which screws into a plate 36 on each of the extensions 33 and 33a, and a clip 37 is interposed between wing-nut 32 and fuse 25 and later arranged between clip 37 and hex nut 34, and spring 27 in turn between nut 34 and plate 36. Clip 37 has a curved end 38 adapted to contact and press against fuse 25 (Figure 3), and an inturned end 39 which works alongside plate 36. 30 By this arrangement spring 27 may be put in position, as shown in Figure 3, and then end 35 of screw 29 screwed into plate 36 to hold spring 27 firmly in position. Then end of fuse 25 may 40 be put in position on the outer side of nut 34 and then clip 37 put in place and nut 32 screwed down to force clip 37 tightly against fuse 25 and so draw down on same to tighten fuse 25 against spring 27 and so produce an adequate tension on the fuse. 45 When the fuse blows, the ends of springs 27 spring outwardly and separate the arc ends and so lengthen the fuse gap and tend to extinguish the arc. Oil is in the outer chamber and also in inner fuse chamber 23, and this is forced outwardly in the chambers and through the apertures 24 and thereby further assists in extinguishing the arc. After operation, a new fuse 25 is inserted, as described above.
- 50 To connect fuse in circuit and also permit insertion and removal of cartridge containing fuse, I show as one arrangement the structure illustrated in Figures 1, 4, 5 and 6. In this arrangement two sets of contact clips are provided, each set comprising clips 40 and 41, having flat shanks 42 and 43 respectively, adapted to be secured to plate 36 by screw 44. Said clips 40 and 41 also have contact portions 45 and 46 respectively, sufficiently separated to permit contact posts 11 to pass between them, but to make firm electrical contact and connection with same. Clips 47 are provided in connection with contacts 41, said clips 47 having outwardly extending portions 48 backing clips 41 and holding same in better 65 contact with posts 11.
- 70 The connection between posts 11, 11 and contact clips or devices 40, 41, is made by turning or partially rotating fuse carrying cartridge 18 so as to cause clips 40, 41 to embrace posts 11, 11, 75 as shown in Figure 5, or else to separate from

said posts by an anti-clockwise movement (indicated by dotted arrows) in Figure 5.

In order to guard against inserting the cartridge 18 into the casing 1 in such a position that contacts 40 and 41 would not engage terminal 5 members 11 within the limits of rotation as above indicated, openings 21a and 21b are provided in flange 14 of casing 1 for receiving the edge portions of extensions 33a and 33, respectively. The edge portion of extension 33a is of less width 10 than the edge portion of extension 33 and slot or opening 21a is of less width than slot or opening 21b, slot 21a being too narrow to receive extension 33. It will therefore be apparent that cartridge 18 can be inserted into place in casing 15 1 in one position only. When inserted in the correct manner contacts 40 and 41 are in position to engage terminals 11 upon rotation of the cartridge 18.

This rotative movement of fuse cartridge to 20 connect and disconnect the fuse in circuit, may be made by turning said cartridge handle 19, either by hand or by inserting a stick, or the like, within opening 19a, and the arrangement is preferably such that the cartridge may be 25 inserted and withdrawn when the fuse is out of circuit, but is locked against insertion and withdrawal when the fuse is in circuit. This prevents the cartridge from being accidentally blown out or other damage done by inadvertently connecting the fuse in circuit when there is a short or other trouble on the line.

This is accomplished by providing a swinging yoke or bail 50 pivoted by pins 51 to sides of casing 1 (Figure 1) so that it may swing into and 35 out of path of cartridge 18 to permit control of the latter's insertion and withdrawal and locking in place. The yoke or bail 50 is preferably provided with an adjustable screw 54 with lock nut 55, and the cartridge handle 19 with channel 56 40 for receiving the end of screw 54. When the cartridge handle 19 is in such position that channel 56 is crosswise of bail 50 to permit screw 54 to move in said channel (Figure 2), contacts 40 and 41 are not connected to posts 11, 11 and 45 cartridge may safely be inserted and withdrawn, and the bail 50 may be swung to bring screw 54 into and out of said channel. If screw 54 is moved out of said channel, bail 50 is swung to one side and cartridge may be removed. If, however, 50 when screw 54 is in channel 56, cartridge is turned to bring contacts 40, 41 in contact with posts 11, the fuse is connected in circuit, but at the same time channel is inclined so that screw 54 cannot move out of channel 56 (see Figure 1), 55 and so fuse cartridge is locked against being withdrawn or blown out.

Means is further provided to prevent rotation of cartridge 18 which would bring contacts 40 and 41 into engagement with posts or terminals 60 11 after the cartridge has been rotated to effect a disengagement thereof and the bail 50 has been lowered into its horizontal position. Such means comprises a lug 60 disposed on the bail 50 and a stop pin 62 fixed to the casing 1. Lug 65 60 is normally disposed below the top 64 of cartridge 18 when the bail is vertically disposed whereby the bolt 54 engages in channel 56 but is adapted, upon rotation of bail 50, to move through opening 66 in top 64 into opposite relation to shoulder 68 defining one end of opening 66. As shown in Figure 2 of the drawings, the top 64 is provided with an arrow 70 indicated in full to show the position thereof when the cartridge is in its "off position", that is, when con- 70 75

tacts 40 and 41 are out of engagement with the terminals or posts 11 and indicated in dotted lines to show the position thereof when the cartridge is in its "on position", namely, when the contacts 40 and 41 are in engagement with terminals 11. Rotation of cartridge 18 between its "off" and "on" positions is limited by stop pin 62 engageable with lug 72 when in "off" position and with lug 74 when in "on" position. 5
 10 Precaution has been taken, therefore, to provide a fuse cutout in which the fuse cartridge can be inserted in place in one position only, and can be inserted and withdrawn only when the fuse is out of circuit, provision also being made to prevent placing said fuse in circuit prior to the locking of the same after insertion or when said locking means is ineffective when the cartridge is disposed for withdrawal.

A pipe 58 leading into the top of casing 1 is 20 provided which serves as a cushion or expansion chamber whenever a heavy circuit is interrupted within the oil fuse cutout and to prevent an undue severe strain from being put on the housing or casing 1.

25 It will be understood that changes and modifications may be made without departing from the spirit of the invention.

I claim:

30 1. An oil switch comprising an outer casing, an inner casing adapted to be inserted into and withdrawn from the outer casing and carrying a fuse under spring tension, and contact devices on the inner and outer casings for making connection to include the fuse in circuit when the 35 inner casing is inserted and given a partial rotation, one of said contact devices being carried by said inner casing and being disposed in spaced relation to said outer casing and the other of said contact devices extending through the 40 end wall opposite the open end of said outer casing and into the same, said contact devices comprising contact posts and open-jawed spring clips to clasp and make contact with said posts.

2. An oil switch comprising an outer casing, 45 an inner casing adapted to be inserted into and withdrawn from the outer casing and carrying a fuse under spring tension, contact devices on the inner and outer casings for making connection to include the fuse in circuit when the inner 50 casing is inserted and given a partial rotation, one of said contact devices being carried by said inner casing and being disposed in spaced relation to said outer casing and the other of said 55 contact devices extending through the end wall opposite the open end of said outer casing and into the same, said contact devices comprising contact posts and open-jawed spring clips to clasp and make contact with said posts, and cooperating 60 clips to back spring clips and help maintain close connection.

3. An oil switch comprising an outer casing, an inner casing adapted to be inserted into and withdrawn from the outer casing and carrying 65 a fuse under spring tension, contact devices on the inner and outer casings for making connection to include the fuse in circuit when the inner casing is inserted and given a partial rotation, said contact devices comprising contact posts extending through the end wall opposite the open end of said outer casing and into the same and open-jawed spring clips connected to said inner casing to clasp and make contact with said posts, cooperating clips to back spring 70 clips, and means whereby the inner casing may 75

be locked against insertion and removal when the fuse is connected in circuit.

4. An oil switch comprising an outer casing, an inner casing adapted to be inserted into and withdrawn from the outer casing and carrying a fuse under spring tension, contact devices on the inner and outer casings for making connection to include the fuse in circuit when the inner casing is inserted and given a partial rotation, said contact devices comprising contact posts and open-jawed spring clips to clasp and make contact with said posts, cooperating clips to back spring clips, and means whereby the inner casing may be locked against insertion and removal when the fuse is connected in circuit, said means comprising a locking bail, and cooperating means on said ball and inner casing operable only when said fuse is out of said circuit permitting movement of said bail. 10 15

5. An oil switch comprising an outer casing, 20 an inner casing adapted to be inserted into and withdrawn from the outer casing and carrying a fuse under spring tension, contact devices on the inner and outer casings for making connection to include the fuse in circuit when the inner casing is inserted and given a partial rotation, said contact devices comprising contact posts and open-jawed spring clips to clasp and make contact with said posts, cooperating clips to back 25 said spring clips, and means whereby the inner 30 casing may be locked against insertion and removal when the fuse is connected in circuit, said means comprising a locking bail and means whereby said bail may prevent and permit the insertion and withdrawal of inner casing, said 35 bail being provided with an adjustable screw and the inner casing with a channel to receive said screw and permit or prevent movement of screw in channel according to position of inner casing. 40

6. An oil fuse comprising an outer casing and a fuse cartridge insertable into said casing, said cartridge having a fuse chamber and oppositely disposed laterally extending portions, a fuse extending through said chamber and having its ends connected to opposite faces of said portions, and springs on said oppositely disposed faces adapted to engage and press transversely on said fuse to maintain said fuse within said chamber under tension. 45 50

7. An oil fuse comprising an outer casing and a fuse cartridge insertable into said casing, said cartridge having a fuse chamber and oppositely disposed laterally extending portions, posts arranged on opposite faces of said portions, a fuse 55 extending through said chamber and having its ends connected to said oppositely disposed posts, springs connected to said posts between said portions and fuse adapted to engage and press transversely on said fuse to maintain said fuse under tension, and spring clips connected to said posts exteriorly of said fuse to form a backing for the same. 60

8. An oil fuse comprising an outer casing and a fuse cartridge insertable into said casing and 65 provided with fuse and spring clips arranged to press transversely of fuse at ends of same and thereby maintain fuse under tension, said fuse being extended to posts and spring clips being interposed between fuse and posts and pressing 70 outwardly on fuse, said posts having abutments for fuse and spring clips and other clips on post to assist in tightening fuse against spring clips. 75

9. An oil fuse comprising an outer casing and a fuse cartridge insertable into said casing and 75

provided with fuse and spring clips arranged to press transversely of fuse at ends of same and thereby maintain fuse under tension, said fuse being extended to posts and spring clips being interposed between fuse and posts and pressing outwardly on fuse, said posts having abutments for fuse and spring clips and other clips on post to assist in tightening fuse against spring clips, and contact devices for including fuse in circuit, 10 said devices being mounted on and secured to metal plate which also carries said spring and fuse arrangement.

10. A switch comprising an outer casing, an inner casing adapted to be inserted into and withdrawn from the outer casing and carrying a fuse, contact devices on the inner and outer casings for making connection to include the fuse in circuit, and means for locking said inner casing to said outer casing, and control means 15 associated with said first-named means whereby said first-named means is operable from locking to unlocking position to permit withdrawal of said inner casing only when said fuse is out of circuit.

11. A switch comprising an outer casing, an inner casing adapted to be inserted into and withdrawn from the outer casing and carrying a fuse, contact devices on the inner and outer casings for making connection to include the 20 fuse in circuit when the inner casing is inserted and given a partial rotation, means for locking said inner casing to said outer casing, and means preventing said rotation when said locking means is in its unlocked position.

12. A switch comprising an outer casing, an inner casing adapted to be inserted into and withdrawn from the outer casing and carrying a fuse, contact devices on the inner and outer casings for making connection to include the 25 fuse in circuit when the inner casing is inserted and given a partial rotation, and means for locking said inner casing to said outer casing, said means being operable to unlock only after rotation to move said fuse out of circuit.

13. A switch comprising an outer casing, an inner casing adapted to be inserted into and withdrawn from the outer casing and carrying a fuse, contact devices on the inner and outer casings for making connection to include the 30 fuse in circuit when the inner casing is inserted and given a partial rotation, means for locking said inner casing to said outer casing, and means to prevent said rotation to place said fuse in circuit until after said locking means has been operated 35 to lock said inner casing to said outer casing, said locking means being operable to unlock only after rotation to move said fuse out of circuit.

14. A switch comprising an outer casing, an inner casing adapted to be inserted into and withdrawn from the outer casing and carrying a fuse, contact devices on the inner and outer casings for making connection to include the fuse in circuit when the inner casing is inserted and given a partial rotation, pivotal locking means 40 on said outer casing cooperating with said inner casing to lock said casings together, and cooperating means on said locking means and inner and outer casings preventing rotation of said inner casing when said locking means is in its 45 unlocked position.

15. A switch comprising an outer casing, an inner casing adapted to be inserted into and withdrawn from the outer casing and carrying a fuse, contact devices on the inner and outer casings for making connection to include the fuse in 50

circuit when the inner casing is inserted and given a partial rotation, pivotal locking means on said outer casing cooperating with said inner casing when said inner casing has been rotated to place said fuse in circuit to lock said casings, 5 and cooperating means on said locking means and inner casing preventing said rotation to place said fuse in circuit when said locking means is in its unlocked position.

16. A switch comprising an outer casing member, an inner fuse carrying member adapted to be inserted into and withdrawn from the outer member, contact devices on the inner and outer members for making connection to include the fuse in circuit when the inner member is disposed within said outer casing, means for locking said inner member to said outer member, cooperating means on said inner and outer members for preventing introduction of said fuse into said circuit when said locking means is inoperative to lock 20 said inner member in said outer member, and means for preventing operation of said locking means from locking to unlocking position while said fuse is in circuit.

17. A switch comprising an outer casing member, an inner fuse carrying member adapted to be inserted into and withdrawn from the outer member, contact devices on the inner and outer members for making connection to include the fuse in circuit when the inner member is disposed within said outer casing, and cooperating means on said inner and outer members for locking said inner member to said outer member, said locking means being so constructed and arranged that movement of said locking means 35 from locking to unlocking position is prevented until said fuse is withdrawn from said circuit.

18. A switch comprising an outer casing member, an inner fuse carrying member adapted to be inserted into and withdrawn from the outer member, contact devices on the inner and outer members for making connection to include the fuse in circuit when the inner member is disposed within said outer casing, means for locking said inner member to said outer member, 40 and means for preventing introduction of said fuse into said circuit when said locking means is inoperative to lock said inner member in said outer member, and means for preventing operation of said locking means from locking to unlock- 50 position while said fuse is in circuit.

19. A switch comprising an outer casing, an inner casing adapted to be inserted into and withdrawn from the outer casing and carrying a fuse, contact devices on the inner and outer casings for making connection to include the fuse in circuit when the inner casing is inserted and given a partial rotation, pivotal locking means on said outer casing cooperating with said inner casing to lock said casings together, and said 55 locking means and inner casing having means normally cooperating to lock said inner casing to said outer casing, said means being so constructed and arranged as to be operable to permit operation of said pivotal locking means from locking to unlocking position only when said fuse is out of circuit.

20. A switch comprising an outer casing, an inner casing adapted to be inserted into and withdrawn from the outer casing and carrying a fuse, contact devices on the inner and outer casings for making connection to include the fuse in circuit when the inner casing is inserted and given a partial rotation, pivotal locking means on said outer casing cooperating with 70

75

8 said inner casing when said inner casing has
9 been rotated to place said fuse in circuit to lock
10 said casings, and said locking means and inner
11 casing having cooperating means preventing ro-
12 tation of said inner casing to place said fuse in
13 circuit when said locking means is in its unlocked
14 position, and means normally cooperating to lock
15 said inner casing to said outer casing, said means
16 being so constructed and arranged as to be op-
17 erable to permit operation of said pivotal locking
18 means from locking to unlocking position only
19 when said fuse is out of circuit.

20 21. A switch comprising an outer casing, an
21 inner casing adapted to be inserted into and
22 withdrawn from the outer casing and carrying a
23 fuse, contact devices on the inner and outer
24 casings for making connection to include the
25 fuse in circuit when the inner casing is inserted
26 and given a partial rotation, a locking bail piv-
27 oted to said outer casing and having an inwardly
28 disposed member engageable with said inner
29 casing for locking the same in said outer casing,
30 and cooperating lugs on said bail and inner and
31 outer casings preventing rotation of said inner
32 casing when said ball is in its unlocked position.

33 22. A switch comprising an outer casing, an
34 inner casing adapted to be inserted into and
35 withdrawn from the outer casing and carrying a
36 fuse, contact devices on the inner and outer
37 casings for making connection to include the fuse
38 in circuit when the inner casing is inserted and
39 given a partial rotation, a locking bail pivoted to
40 said outer casing and having an adjustable in-
41 wardly disposed member engageable with said in-
42 ner casing for locking the same in said outer
43 casing, and cooperating lugs on said bail and
44 inner and outer casings preventing rotation of
45 said inner casing when said ball is in its unlocked
46 position.

47 23. A switch comprising an outer casing mem-
48 ber, an inner fuse carrying member adapted to
49 be inserted into and withdrawn from said outer
50 member, contact devices on the inner and outer
51 members for making connection to include the
52 fuse in circuit when the inner member is dis-
53 posed within said outer casing, said inner mem-
54 ber having a channel, and swingable locking
55 means for said inner member provided with a
56 portion adapted to be received in said channel,
57 said channel having means disposed to receive
58 said portion only when said fuse is out of circuit.

59 24. A switch comprising an outer casing mem-
60 ber, an inner fuse carrying member adapted to be
61 inserted into and withdrawn from said outer
62 member, contact devices on the inner and outer
63 members for making connection to include the
64 fuse in circuit when the inner member is disposed
65 within said outer casing, said inner member hav-
66 ing a channel, and swingable locking means for
67 said inner member provided with a portion
68 adapted to be received in said channel, said chan-
69 nel having means disposed to receive said portion
70 only when said fuse is out of circuit and to prevent
71 removal of said portion therefrom to unlock said
72 locking means when said fuse is in circuit.

73 25. A switch comprising an outer casing mem-
74 ber, an inner fuse carrying member adapted to
75 be inserted into and withdrawn from said outer
76 member, contact devices on the inner and outer
77 members for making connection to include the
78 fuse in circuit when the inner member is dis-
79 posed within said outer casing, said inner mem-
80 ber having a channel, and swingable locking
81 means for said inner member provided with a
82 portion adapted to be received in said channel,

83 said channel having means disposed to receive
84 said portion only when said fuse is out of cir-
85 circuit, and means preventing movement of said
86 fuse into circuit until after said portion is re-
87 ceived in said channel. 5

88 26. A switch comprising an outer casing mem-
89 ber, an inner fuse carrying member adapted to be
90 inserted into and withdrawn from said outer
91 member, contact devices on the inner and outer
92 members for making connection to include the
93 fuse in circuit when the inner member is dis-
94 posed within said outer casing, said inner mem-
95 ber having a channel, and swingable locking
96 means for said inner member provided with a
97 portion adapted to be received in said channel, 10
98 said channel having means disposed to receive
99 said portion only when said fuse is out of cir-
100 circuit and to prevent removal of said portion
101 therefrom to unlock said locking means when
102 said fuse is in circuit, and means preventing
103 movement of said fuse into circuit until after
104 said portion is received in said channel. 15

105 27. A switch comprising an outer casing mem-
106 ber, an inner fuse carrying member adapted to be
107 inserted into and withdrawn from said outer
108 member, contact devices on the inner and outer
109 members for making connection to include the
110 fuse in circuit when the inner member is dis-
111 posed within said outer casing, said inner mem-
112 ber having a channel, and swingable locking
113 means for said inner member provided with a
114 portion adapted to be received in said channel,
115 said channel having means disposed to receive
116 said portion only when said fuse is out of circuit,
117 and means on said outer member and locking
118 means cooperating with said inner member pre-
119 venting movement of said fuse into circuit until
120 after said portion is received in said channel. 20

121 28. A switch comprising an outer casing mem-
122 ber, an inner fuse carrying member adapted to
123 be inserted into and withdrawn from said outer
124 member, contact devices on the inner and outer
125 members for making connection to include the
126 fuse in circuit when the inner member is dis-
127 posed within said outer casing, said inner mem-
128 ber having a channel, and swingable locking
129 means for said inner member provided with a
130 portion adapted to be received in said channel,
131 said channel having means disposed to receive
132 said portion only when said fuse is out of circuit
133 and to prevent removal of said portion therefrom
134 to unlock said locking means when said fuse is
135 in circuit, and means on said outer member and
136 locking means cooperating with said inner mem-
137 ber preventing movement of said fuse into cir-
138 circuit until after said portion is received in said
139 channel. 30

140 29. In a switch, the combination of a rotatable
141 support, contact devices on opposite faces of said
142 support and disposed in opposed relation, each
143 of said devices comprising spring clips connected
144 to said support at one end and being spaced apart
145 at the other end, and a backing clip connected
146 at one end to said support and having the re-
147 maining portion thereof in backing relation to 40

148 one of said clips. 45

149 30. In a switch, the combination of a support
150 provided with terminals, a fuse extending there-
151 between, springs adjacent the end portions of
152 said fuse, and oppositely disposed clip members, 50
153 said springs and clip members acting to hold
154 said fuse taut. 70

155 31. In a switch, the combination of a support
156 provided with terminals, a fuse extending there-
157 between, springs adjacent the end portions of 75

said fuse and engaging the faces of said fuse, and oppositely disposed clip members engaging the opposite faces of said fuse in spaced relation to said springs whereby said fuse is maintained in taut relation therebetween.

32. An oil fuse comprising an outer casing and a fuse cartridge insertable into said casing, said cartridge having a transverse fuse chamber and oppositely disposed openings in the wall of said chamber and leading into the same, a fuse extending through said openings and being connected adjacent its ends to said cartridge exteriorly of said chamber, and springs connected to said cartridge adjacent the ends of said fuse and cooperating therewith to maintain said fuse within said chamber under tension.

33. A switch comprising an outer casing, an inner fuse carrying member adapted to be inserted into and withdrawn from said outer casing, contact devices on the inner member and on said outer casing for making connection to include the fuse in circuit when the inner member is disposed within said outer casing, and a swingable locking member for said inner member, one of said members having a channel and the other of said members having means adapted to be received in said channel, said channel having means disposed to receive said last-named means only when said fuse is out of circuit.

34. In a switch, the combination of a fuse cartridge having a fuse chamber provided with oppositely disposed openings in the wall of said chamber and leading into the same, contact devices secured to said cartridge in opposed relation exteriorly of said chamber, a fuse extending through said openings and being connected adjacent its ends to said contact devices, and springs connected to said cartridge and cooperating with said fuse to maintain the same within said chamber under tension.

35. In a switch, the combination of a fuse cartridge having a fuse chamber provided with op-

ositely disposed openings in the wall of said chamber and leading into the same, contact devices secured to said cartridge in opposed relation exteriorly of said chamber, said devices including an electrical conducting member secured to opposite faces of said cartridge, a fuse extending through said openings and being connected adjacent its ends to said members, and springs connected to said members and cooperating with said fuse to maintain the same within said chamber under tension.

36. In a switch, the combination of a fuse cartridge having a fuse chamber provided with oppositely disposed openings in the wall of said chamber and leading into the same, electrical conducting members secured to opposite faces of said cartridge, spring clips connected to said members in opposed relation, a fuse extending through said openings and being connected adjacent its ends to said members, and a spring connected to each of said members and cooperating with said fuse to maintain the same within said chamber under tension.

37. In a switch, the combination of a fuse cartridge having a fuse chamber provided with oppositely disposed openings in the wall of said chamber and leading into the same, electrical conducting members secured to opposite faces of said cartridge, open-jawed spring clips connected to said members in opposed relation, a backing clip connected to each of said members and having a portion thereof in backing relation to the outer of said spring clips, a fuse extending through said openings and being connected adjacent its ends to said members, a spring connected to each of said members and cooperating with said fuse to maintain the same within said chamber under tension, and a spring clip connected to each of said members forming a backing for said fuse.

ANDREW E. PAPP.
